UNITED STATES PATENT OFFICE.

CHARLES K. ERNST, OF BUFFALO, NEW YORK.

PROTECTING DEVICE FOR AREAWAYS AND THE LIKE.

Application filed April 24, 1926. Serial No. 104,389.

This invention relates to a protecting device for areaways and elevator shafts whereby the opening around such areaways or shafts is enclosed and persons are prevented 5 from accidentally stepping into the same and becoming injured.

It is the object of this invention to provide a protecting device of this character which is automatic in its operation, so that 10 upon opening and closing the door or cover forming the closure of the areaway or shaft will operate to fold and unfold a fence or guard device on the sides of the areaway or shaft, and the rising and falling of the hoisting 15 device in the areaway or shaft will cause the door or cover to be opened or closed and also move a foldable gate into and out of its operative position along the areaway or shaft between the fence portions of the guard.

20 In the accompanying drawings:

Figure 1 is a perspective view of an areaway arranged in the side-walk adjacent to a building and equipped with an approved form of protecting device, which embodies 25 my invention, showing the parts in their operative position.

Figure 2 is a fragmentary vertical section, on an enlarged scale, of the areaway and the protecting device associated therewith showing the parts in their inoperative position.

30 Figure 3 is a fragmentary front view, partly in section, of the areaway and the protecting device associated therewith, showing the gate in its folded or open position.

Figure 4 is a vertical section taken on line 4—4, Figure 1.

Figure 5 is a fragmentary horizontal section taken through the mast of the hoisting 40 apparatus in the areaway and showing its connection with the gate of the areaway guard.

Similar characters of reference indicate 45 corresponding parts in the several views of the drawings.

Although this invention is applicable to areaways and elevator shafts of various forms, the same is shown in the present instance in connection with an areaway 10, which is arranged in the side-walk adjacent to a building and associated with a hoisting apparatus whereby ashes and other materials may be raised from the basement of the building through the areaway and disposed upon the side-walk or street or into a wagon intended to receive same,

This areaway is normally covered at its upper end so as to prevent anything from accidentally falling into the same and for this purpose a vertically swinging door or 60 cover 11, is employed which is pivotally mounted at its inner horizontal edge by a hinge 12 or otherwise, on the inner side wall of the areaway whereby this door can be either lowered into its horizontal normal position in which it closes the areaway, as shown in Figure 2, or same may be raised into its vertical inoperative position in which the areaway is uncovered, as shown in Figure 1.

In order to prevent persons from accidentally stepping or falling into the areaway when the same is open, a protecting device is provided which extends around the sides of the areaway above the side-walk when the door is open. For this purpose the protecting device comprises a foldable gate which is adapted to be arranged above the areaway on that side thereof opposite to the hinge of the door, and two fence sections are provided which are normally arranged along the transverse sides of the areaway above the sidewalk and between the corresponding vertical edges of the gate and the door.

Each of these fence sections comprises an upright post 13, which is pivoted at its lower end by means of a pin 14, or otherwise, to the inner side of the areaway adjacent to one of its outer corners, so that this post can swing about a horizontal axis, a 90 cleat 15 secured to the inner side of the door adjacent to one of its edges, upper and lower rails which are normally arranged parallel and horizontal and each of which consists of a bar having outer and inner rail bars 16 and 17, which are pivotally connected at their inner or opposing ends by means of a pin or rivet 18, while their outer ends are connected pivotally with the post 13 and the cleat 15, by means of pivots 19 and 20,

100 as shown in Figures 1 and 2. When the door 11 is in its closed or horizontal position each of the fence sections is folded, as shown in Figure 2, during which time the post 13 is arranged horizontally and the 105 bars of the fence rails project in a downwardly converging relation, relatively to each other. Upon raising the door 11 into its open position the several members of each fence are automatically unfolded into the 110 position in which they form an obstruction or fence across the respective sides of the

areaway, at which time the post 13 is in an upright position and the members of each rail are unfolded into a horizontal position, as shown in Figure 1. The unfolding movement of the bars of each rail is limited just before same reach a dead center so that when the door 11 is again lowered into its closed position, the bars of each fence rail will turn relatively to each other and automatically assume a folded position.

Although various forms of stops may be used for accomplishing this purpose, it is preferable to employ a stop plate 21 which is secured to the lower edge of one of the fence rail bars, adjacent to the pivot 18 thereof and adapted to engage with the underside or the lower edge portion of the companion rail bar, as shown in Figure 1. This manner of stopping the unfolding movement of the rail bars is not only very simple and inexpensive but also adds to the strength of the fence as a whole when the same is unfolded into its operative position. Although each of the fence sections shown in Figure 1 is provided with upper and lower foldable rails it is obvious that one or the other of these rails may be omitted and that additional rails may be employed if desired, the number of rails being determined by the extent of safety which a particular installation requires.

In areaways of this character a hoisting device is frequently employed for elevating material such as ashes from the basement to the side-walk and street and it is the intention in the present case to utilize the motion of such an elevator to automatically open and close the door or cover 11 and thereby also automatically move the fence sections into and out of their operative protecting position. This elevator in the present case comprises a mast arranged within the areaway adjacent to one of the outer corners thereof and composed of a lower fixed section 22, and an upper vertically movable section 23 which is guided on the lower section of the mast. Various means may be employed for raising and lowering the upper section of the mast relatively to the lower section thereof, but as the same form no part of the present invention it is deemed unnecessary to enter into a detailed description and illustration of same.

On the upper end of the movable mast section is mounted a hoisting drum 24, upon which a cable 25 is wound which latter has a hook 26 at its free end for attachment to the load to be hoisted, such as ash barrels, or other materials which are to be removed from the basement to the exterior of the building. This drum may be operated in any approved manner. When the hoist is not in operation the upper mast section is lowered together with the hoisting drum and associated parts so that all parts of the hoist

are below the door or cover 11 when the latter is closed, as shown in Figure 2. When it is desired to use the hoist the upper mast section is elevated, as shown in Figure 1, thereby bringing the hoisting drum above the level of the side-walk a sufficient distance so that any load which is hoisted or raised through the areaway may be removed laterally from the hoisting line or cable to the side-walk, street or wagon intended to receive same.

For the purpose of causing the door 11 to be automatically opened and closed during the rising and lowering motion of the upper mast section, a connection is provided between these members which in its preferred form consists of a lifting link bar or member 27, which is pivotally connected at its lower end by means of pin 28, to the lower part of the movable mast section, while its upper end is pivotally connected by means of a pin 29, with the under side or inner side of the door at a point between its hinged and free edge as shown in Figures 1 and 2.

It follows from this construction that when the upper mast section is lowered the link 27 will automatically swing the door 11 downwardly into a horizontally closed position and when this mast section is raised to its fullest extent, the link 27 will open the door into a vertical position, as shown in Figure 1, and that this door will be positively held in either of these extreme positions when the movable mast section is lowered or raised and thereby preventing interference in the operation of these parts but instead insuring harmonious action of the several members associated therewith.

The gate herein before mentioned is adapted to close the space between the outer ends of the two fence sections and the same is foldable so that same can be conveniently opened or closed to permit the load which has been lifted by the hoisting apparatus, to be swung laterally from over the areaway to one side thereof, for instance the curb of the roadway. In the preferred organization this gate is mounted on the movable or upper mast section so that the gate is automatically raised into its operative position between the fence sections when the hoisting apparatus is in use and is also automatically lowered with the hoisting apparatus into the areaway when the hoisting apparatus is not in use and the areaway is closed by the door.

Although various means may be employed for accomplishing this purpose those shown in the drawings have been approved inasmuch as they have been satisfactory in actual practice. As there shown, a guideway 30 is provided for the gate which is movable vertically in the areaway with the upper mast section of the hoisting apparatus, which guideway in the present instance is

constructed in the form of a channel arranged horizontally and lengthwise adjacent to the outer wall of the areaway and connected at one end by means of bracket 32 with the movable mast section 23, as best shown in Figure 5. The gate is composed of a plurality of foldable upright bars or slats 39 which are laid across each other in the form of lattice work and pivotally connected at the several crossing points, by means of pins or rivets 33 so that the several gate bars can be folded or unfolded and thereby either contract the gate or extend the same lengthwise in the form of "lazy-tongs." The lower ends of the several bars of the foldable gate are guided at their lower ends in the guideway 30, which is supported on the upper end, or movable mast member, so that upon projecting or contracting the gate bars, the same will form a closure across the outer side of the areaway, between the outer ends of the fence sections.

In order to retain these gate bars in their proper position relative to the areaway and the hoisting apparatus, and still permit the same to be folded and unfolded, an upright guide plate 34 is mounted on the outer side of the upper part of the movable mast section and this plate is provided with slots 35 which receive the adjacent pivots 36 which connect adjacent bars of the foldable gate, as shown in Figures 1 and 4. By these means the bars of the gate may be freely unfolded and folded so as to either clear or obstruct the gate way as required and still maintain the gate in its proper relation to the areaway and the hoisting apparatus.

This gate may be opened and closed manually if desired but it is preferable to provide means which operate constantly and automatically to hold the parts of the gate in a position in which the same close the gate way but permitting same to be opened readily manually at will.

Two cooperating bars of the gate, for example the two bars at the extreme left hand end of the gate adjacent to the hoisting apparatus are connected by means of a spring 37, which is adapted to be stretched or extended when the several bars of the gate are folded for opening the gate way, thereby causing this spring to constantly tend to close the gate by drawing together the bars with which it is connected and thereby automatically close the gate when same is released after having been opened manually.

In order to prevent the gate when in its extended or closed position from projecting beyond the guide way 30, and possibly interfering with other adjacent parts on the walls of the areaway, a stop 38 is provided on the outer end of the guide way 30 which is adapted to be engaged by the respective end of the gate when the latter is

in its fully closed position and thereby avoid interference as above described.

From the foregoing description it will now be apparent that this entire protecting device for areaways or elevator shafts is automatic in its operation, that is to say, when the hoisting apparatus is raised into its operative position the door over the areaway will be opened and the two fence sections and the gate forming the protecting device will be unfolded or moved into their operative position, and when the hoisting device is lowered into an inoperative position the door will be automatically closed and both the fences and the gate of the protecting device will be folded into their inoperative position below the door and into the areaway, so that no part of the areaway will be left in an exposed and dangerous condition through over-sight on the part of an attendant.

Moreover this protecting device is very simple in construction, the several parts are so organized that they are not liable to get out of order, and owing to the simplicity of the several members, the same can also be produced at a comparatively low cost.

I claim as my invention:

1. A protecting device for areaways, comprising a door pivoted at one end to one side of said areaway so that it can be lowered into its closed horizontal position over said areaway and raised into a vertical open position, and a guard connected with said door and movable into its operative position along side of the areaway upon opening the door and into its inoperative position within the areaway upon closing the door, said guard comprising foldable members pivotally connected with each other and with said areaway and door, respectively. 95

2. A protecting device for areaways, comprising a door pivoted at one end to one side of said areaway so that it can be lowered into its closed horizontal position over said areaway and raised into a vertical open position, and a guard connected with said door and movable into its operative position along side of the areaway upon opening the door and into its inoperative position within the areaway upon closing the door, said guard comprising a normally upright post pivoted on the side of the areaway opposite the pivot of the door, and two normally horizontal rails consisting of bars having their inner ends pivotally connected with each other and their outer ends pivotally connected, respectively, with the upper end of said post and the inner side of said door. 110

3. A protecting device for areaways, comprising a door pivoted at one end to one side of said areaway so that it can be lowered into its closed horizontal position over said areaway and raised into a vertical open position, and a guard connected with said door 120

and movable into its operative position along side of the areaway upon opening the door and into its inoperative position within the areaway upon closing the door, said 5 guard comprising a normally upright post pivoted on the side of the areaway opposite the pivot of the door, two normally horizontal rails consisting of bars having their inner ends pivotally connected with each 10 other and their outer ends pivotally connected, respectively, with the upper end of said post and the inner side of said door; and a stop arranged on one of said rail bars and adapted to engage the other rail bar 15 for limiting the unfolding movement of said rails.

4. A protecting device for areaways, comprising a door pivoted at one end to one side of said areaway so that it can be lowered 20 into its closed horizontal position over said areaway and raised into a vertical open position, and a guard connected with said door and movable into its operative position along side of the areaway upon opening the door 25 and into its inoperative position within the areaway upon closing the door, said guard comprising a normally upright post pivoted on the side of the areaway opposite the pivot of the door, two pairs of rail bars normally 30 arranged horizontally one above the other, the members of each pair having their inner opposing ends pivotally connected with each other and their outer ends pivotally connected with the upper end of said post 35 and the underside of said door, respectively.

5. A protecting device for areaways, comprising a door pivoted at one end to one side of said areaway so that it can be lowered into its closed horizontal position over said 40 areaway and raised into a vertical open position, and a guard connected with said door and movable into its operative position along side of the areaway upon opening the door and into its inoperative position within the 45 areaway upon closing the door, said guard

comprising a normally upright post pivoted on the side of the areaway opposite the pivot of the door, two pairs of rail bars normally arranged horizontally one above the other, the members of each pair having their inner opposing ends pivotally connected with each other and their outer ends pivotally connected with the upper end of said post and the underside of said door, respectively; and a stop arranged on the inner end of one member of each pair and adapted to engage with the inner end of the companion member of the same pair in the unfolded position of the same. 55

6. A protecting device for areaways, comprising a hoisting apparatus arranged in said areaway and having a vertically movable member, a horizontal track mounted on said vertically movable member, and a guard composed of a plurality of bars which are pivotally connected with each other in the form of lazy-tongs so as to be capable of folding and unfolding horizontally, means for guiding some of the pivots of said guard on said vertically movable member of said hoisting apparatus, and a spring connecting two cooperating members of said guard and operating to hold the latter yieldingly in its unfolded condition. 60

7. A protecting device for areaways, comprising a vertically swinging door pivotally mounted at one end on one side of said areaway, a vertically movable gate adapted to extend along the opposite side of the areaway, foldable fence sections arranged between opposite ends of said gate and door and each connected with said door and areaway, respectively; and a hoisting apparatus arranged in said areaway and having a vertically movable member which carries said 65 gate. 70

In testimony whereof I hereby affix my signature.

CHARLES K. ERNST.
